UNITED STATES PATENT OFFICE

EMILIO ZAGO, OF NEW YORK, N. Y., ASSIGNOR TO UNIVERSAL CLOCK CORPORATION, A CORPORATION OF DELAWARE

DESIGN FOR A CLOCK CASE

Application filed May 8, 1931. Serial No. 39,779. Term of patent 7 years.

To all whom it may concern:

Be it known that I, EMILIO ZAGO, a subject of Italy, residing in the borough of Manhattan, city, county, and State of New York, have invented a new, original and ornamental Design for a Clock Case, of which the following is a specification, reference being had to the accompanying drawing, forming a part thereof.

In the drawing, the figure is a perspective view of a clock case illustrating my new design.

I claim:

The ornamental design for a clock case, substantially as shown.

This specification signed this 24th day of April, 1931.

EMILIO ZAGO.
